RAMP SHOE

Filed June 23, 1923

FIG. 1

FIG. 2

FIG. 4

FIG. 3

Charles A. Parker *Inventor*

By

Herb E. Smith

Attorney

UNITED STATES PATENT OFFICE.

CHARLES A. PARKER, OF HAUGAN, MONTANA.

RAMP SHOE.

Application filed June 23, 1923. Serial No. 647,277.

To all whom it may concern:

Be it known that I, CHARLES A. PARKER, a citizen of the United States, residing at Haugan, in Mineral County and State of 5 Montana, have invented certain new and useful Improvements in Ramp Shoes, of which the following is a specification.

My present invention relates to improvements in ramp shoes for use with ramp controlled train stop mechanism in connection with the automatic application of air brakes on steam railroads and railroads employing electric propulsion.

In the preferred installation of the train 15 stop mechanism I employ a ramp shoe at each side of the train or car, and inasmuch as these shoes are of similar construction I have illustrated and described a single shoe in its relation to the train stop mechanism 20 with which it is also effective.

The primary object of the invention is the provision of a ramp shoe carried by the railroad locomotive or other vehicle, which, in the equipment for steam railroads, is 25 connected with the train stop mechanism usually carried in the cab of the locomotive, and constructed in such manner as to hold the train stop mechanism in running position. By co-action with a ramp rail preferably located outside of the track rail and 30 in the path of movement of the ramp shoe, the latter is moved to permit operation of the train stop mechanism as will be described.

By the utilization of my invention I secure a ramp shoe or contact device which will insure proper contact with the ramp rail whether the train is running forward or running backward. Means are also provided whereby snow or ice are removed from 40 the ramp rail by the movement of the ramp shoe to prevent clogging. The ramp shoe is of simple construction, strong and reliable, and inexpensive in cost of production.

In the accompanying drawings I have 45 illustrated one complete example of the physical embodiment of my invention wherein the parts are combined and arranged in accordance with the best mode I have thus far devised for the practical application of the principles of my invention.

Figure 1 is a view showing the train stop mechanism carried in the locomotive cab, the ramp shoe carried by the locomotive 50 truck and in operative connection with said

mechanism, and the ramp rail at the track-side with which the ramp shoe co-acts.

Figure 2 is a longitudinal sectional view 60 through the flexible, resilient and elastic ramp shoe.

Figure 3 is a perspective view of the ramp shoe.

Figure 4 is a sectional detail view of one of the guide yokes or stirrups carried by the locomotive truck for guiding the movement of the flexible shoe.

In order that the utility of the ramp shoe may readily be understood I have shown in Fig. 1 a bell crank lever 1 pivoted at 2 and designed, when released by the action of the ramp device, to be swung on its pivot. The action of the spring also releases an air valve 4 and the air brakes are automatically applied by reduction of the train line pressure through pipe 5. Details 75 of construction of the train stop mechanism may be found in my co-pending application for patent, Ser. No. 647,276, filed June 23, 1923.

The train stop mechanism is located in 80 the locomotive cab and the lever 1 is connected with the ramp device by means of a flexible cable 6 having an eye bolt 7 and nut 8 for attaching to the bell crank lever.

The flexible ramp shoe is composed of a 85 pair of leaves 9 and 10 secured together at their longitudinal centers and to the truck T by means of a pair of U-shaped bolts 11 and nuts 12.

The leaves are of metal possessing sufficient elasticity and resiliency to pull on the cable 6 and hold the bell crank lever in normal running position and to permit flexing of the shoe at the front and rear as it passes over the ramp rail 13 at the trackside 90

At its ends the ramp shoe is equipped with contact members 14 and 15 which are of box-like construction open at the front and rear, and each member is provided with an upper attaching flange 16. The flange is interposed between the free ends of the spring leaf 9 and the spring leaf 10, and by means of a rivet 17 is secured to the leaf 10 as shown. The two leaves of the resilient and elastic ramp shoe are thus spaced apart at 105 their ends to insure the required rigidity in the shoe and yet provide for the necessary flexing of the shoe as the latter passes over a ramp rail.

The rear contact member 14 has a perfo- 110

rated ear 18 to which the cable 6 is attached and said cable extends upwardly to the train stop mechanism in the housing as shown.

Near the ends of the flexible shoe are provided 5 guide yokes or stirrups 19 each of which has a stud bolt 20 and by means of which the guide stirrup is rigidly attached to the truck T. The flexible shoe is thus permitted to ride up and down or move vertically 10 in the stirrup and is guided therein to prevent lateral movement. The lower cross bar of the yoke or stirrup is fashioned with a knife edge 22 to support the ramp shoe in normal position, and this triangular shaped 15 bar is effective in shedding snow or ice that might otherwise accumulate in the yokes when the shoe is raised. As such an accumulation would result in holding the shoe at a higher elevation than its predetermined location, these devices perform an important 20 function in the operation of the device.

The open end box-like contact members 14 and 15 ride over the ramp rail as indicated in Fig. 1, the forward member sliding 25 flatly over the declining end of the arched ramp rail and the rear member riding on an edge as indicated. Any ice or snow that may accumulate on the ramp rail is thus scraped therefrom and passing through the 30 contact members is disposed of without danger of clogging them. The use of the two members 14 and 15 insures a double contact on the ramp rail and they are adapted for use when the train is moving backward or forward.

In Figs. 2 and 3 the ramp shoe is shown with an arched or curved formation adapting it for use with the arched rail 13, and as the shoe rides along the ramp rail the 40 shoe is partially straightened as indicated in Fig. 1. The straightening or elevating of the rear end of the shoe slackens the cable 6 to permit actuation of the train stop mechanism.

It will be apparent that the shoes may 45 with facility be attached to the truck T, and are held thereto without danger of loss, and in position for reliable operation in the performance of their required functions.

Having thus fully described my invention, 50 what I claim as new and desire to secure by Letters Patent is—

1. A flexible, resilient ramp shoe comprising a pair of leaves joined at their longitudinal centers, means for spacing the free 55 ends of the upper leaf from the lower leaf, and contact members carried at the ends of said shoe.

2. A flexible, resilient ramp shoe comprising a pair of leaves joined at their longitudinal centers, means for spacing the free 60 ends of the upper leaf from the lower leaf, and box-like contact members having open front and rear ends secured at the ends of 65 said shoe.

3. A flexible resilient ramp shoe comprising a pair of leaves joined at their longitudinal centers, box like contact members each having an upper flange attached to the lower leaf and interposed between the free ends 70 of the upper leaf and the lower leaf.

4. In a flexible resilient ramp shoe the combination with a pair of leaves rigidly joined together at one point and adapted for attachment to a support, a contact member having front and rear open ends and an attaching flange on said member located between the free ends of said leaves and attached to one of said leaves.

5. The combination with a support of a 80 flexible resilient ramp shoe having one portion rigidly anchored to said support, a vertically disposed guide yoke on said support, and said yoke having a supporting cross bar for said shoe formed with an upper angular edge.

In testimony whereof I affix my signature.
CHARLES A. PARKER.
